(**) Term: **14 Years**

(57) **CLAIM**

(21) Appl. No.: **29/171,548**

The ornamental design for clip for securing a heat-dissipating module, as shown and described herein.

(22) Filed: **Nov. 25, 2002**

DESCRIPTION

(30) **Foreign Application Priority Data**

Sep. 13, 2002 (TW) 91305156

(51) LOC (7) Cl. **23-04**

FIG. 1 is a perspective view of clip for securing a heat-dissipating module showing our new design;

(52) U.S. Cl. **D23/411**

FIG. 2 is a right side view thereof;

(58) Field of Search D23/411, 370,

FIG. 3 is a top view thereof;

D23/379; 248/500, 505, 694; 361/695,
697, 707; 257/718, 719, 726; 24/295, 296

FIG. 4 is a front view thereof;

(56) **References Cited**

FIG. 5 is a bottom view thereof;

U.S. PATENT DOCUMENTS

FIG. 6 is a left side view thereof; and,

D461,238 S * 8/2002 Horng D23/411

FIG. 7 is a rear view thereof.
